REVERSIBLE STEEL-WOOL MACHINE.

Application filed January 6, 1925. Serial No. 779.

Our present invention relates to steel wool machines of the type commonly employed to cut steel wool from a wire which is reeled back and forth over a suitable bed. Machines of this type commonly employ six cutter holders, operating in tandem on the wire, each holder carrying two oppositely directed cutters so that all the cutter holders may be shifted laterally to bring the properly directed set of cutters into operative engagement with the wire when the direction of reeling of the wire is reversed.

In machines of this type, it has never been found possible to dispense with highly skilled labor for adjusting the individual knives so that they will work properly to cut uniform quality steel wool and while our present invention does not dispense with the necessity for skill, one object is to greatly reduce the number of movements that are required to make the necessary adjustments of cutters, particularly when the direction of the wire is reversed. One important time and labor saving feature is arranging for a simultaneous shift or what we term a universal traverse whereby a single hand movement operates to cause the desired lateral shift of all the cutter stands. At the same time, each stand is individually adjustable with respect to the shifting mechanism so that each pair of knives may be given an independent lateral adjustment to bring different portions of its cutting edge into operative engagement with the wire. That is to say, the individual transverse adjustments which may be necessary at any moment, are relative to and superposed upon the simultaneous or universal transverse adjustment which is used only when the direction of pass of the wire is reversed.

Another important feature of our invention involves making the knife holders more compact so that more of them can be operated on a drawing bed of ordinary length. In the specific machine here illustrated, the frame, bed and reeling mechanism of the machine is of standard commercial design and length originally equipped with six pairs of oppositely directed cutters, whereas our present invention makes possible the use of twelve or even fourteen pairs of cutters, though but eleven are shown in the drawing. The reason only six cutters have been used

in tandem on the prior machines is that the cutter blades have been non-adjustably clamped on the ends of relatively long levers, extending parallel to the wire, the adjustment of the cutter being effected by having said levers on pivots and locked in desired angular relation by set screws engaging each arm on opposite sides of its pivotal axis. When the depth of cut was to be varied, both of these screws had to be operated, one being backed off and the other tightened, for each of the blade holding levers. In place of this cumbersome arrangement, we provide a simple vertically slidable block, in a slot of which the cutting blade is held by a clamping screw. The bed of the slot is at a fixed angle to the wire so that we avoid the change of cutting angle which is unavoidable in the pivoted forms of knife holder above described. The adjustment in our device is effected entirely by rotation of a vertical screw engaging the blade holding block.

The above simplified construction, wherein relatively long pivotal tool holders are dispensed with, makes it possible to place the knives much nearer together.

Another feature of our invention is arranging the tool holders so close together, that oppositely directed blades of adjacent holders can operate upon the same bed piece. Another improvement made possible by this proximity is arranging an air blast for non-positively floating the cut steel wool laterally away from the knife edges and the wire by means of an air jet from a single nozzle which is flattened so that one lateral edge of the jet sweeps the working edge of one knife when the wire is moving in one direction and the other edge sweeps the working edge of the oppositely directed knife of the adjacent stand, when the wire is moving in the other direction.

The specific material which we prefer to employ is steel wire or material of circular cross section such as is commonly supplied in bundle coils. The machine, however, is capable of operating on steel or other material in other forms, such, for instance, as metallic wires, rods and bands of triangular, rectangular or other polygonal cross section and in fact may operate under some circumstances on plate or sheet material. In so far

as the present invention is concerned, the machine is capable of operating on materials other than the steel and of grooving for purposes other than the production of the specific product above mentioned.

The above and other features of our invention will be more evident from the following description in connection with the accompanying drawings, in which—

10 Fig. 1 is a view in side elevation of a machine embodying the invention;

Fig. 2 is a transverse sectional view on the line 2—2 of Fig. 1;

15 Fig. 3 is a fragmentary longitudinal sectional view on the line 3—3 of Fig. 2;

Fig. 4 is a sectional plan view on the line 4—4 of Fig. 2.

The machine includes a table 10, supported upon a pair of longitudinally extending 20 integrally connected beams 11, which are in turn supported at each end upon a pair of sturdy legs 12. This rather heavy frame construction prevents undue vibration when the machine is in operation and affords a 25 convenient mounting for the reels 13 which are borne in brackets 14 projecting endwise from the legs of the table. The transverse webs 15 which connect beams 11 offer a support for a longitudinally extending bed bar 30 16 accommodated in a cut away portion 17 of the table and having a curved upper edge which is highest at the center of the table. Bed blocks 18 are disposed within a slot 16^a in the upper surface of bed bar 16 and are 35 curved longitudinally in conformity with the bed bar. Each block is vertically adjustable upon a pair of supporting screws 19 and is locked against movement by one or more set screws 20. Aligned grooves 21 in the upper 40 surfaces of the blocks receive and guide a wire 22 or other strip of material being worked upon.

The reels are below the table 10 and due to the longitudinal curvature of the bed, a 45 downward stress is always exerted on the wire as it is dragged over the bed from one reel to the other, so that it is held firmly in the guide grooves, 21. Reels 13 are reversible both as to direction of rotation and direction of transverse feed for purposes of 50 properly coiling the wire and they have releasable friction brakes whereby the supply reel affords proper resistance for maintaining suitable tension on the wire to prevent 55 overrunning. Inasmuch as all of these features are conventional in machines of this character, they have not been illustrated. The reels serve alternately as traction and supply reels to draw the wire under tension 60 alternately in opposite directions over the bed, and we may employ any suitable number of straightening rolls 24 at each end of the table to prevent kinking of the wire and insure a smooth feed.

65 Tool stands 25 are mounted for movement

transversely of the table in undercut guide ways 26 and each stand carries a pair of oppositely facing knives or grooving tools 27, 27^a. The tool set 27 operates upon the wire as it is passed in one direction and set 27^a is used when the wire travels in a reverse direction, the tool stands being shifted in the guide ways, upon each reversal of the wire to bring the proper set of tools into position.

One feature of the invention is the elimination of the conventional slow and clumsy adjustment of the knives to lower them as the wire becomes thinned after repeated grooving operations. With this end in view, we mount the tools in inclined slots 28 in 75 vertically sliding tool holding blocks 29 guided in side plates 30 of the tool stands. Each block is vertically adjustable by means of a single screw 31 rotating in the top plate 32 of the tool stand. Milled handle nuts 33 on the projecting upper end of the screws offer a convenient means for manually adjusting the blocks. To clamp the tools firmly in place within the slots 28, we may employ 80 clamping screws 34 extending diagonally 90 through the blocks 30 and clamping the tools against the bottom of the inclined slots. The direct vertical adjustment of the tools not only saves a great amount of space heretofore occupied by the longitudinally extending 95 adjusting levers, but permits an unvarying cutting angle to be maintained between the tool and work in all adjustments of the tool holders. The stands are so close together that the ends of oppositely facing 100 tools of adjacent stands may alternately work on opposite ends of the same bed block and as noted above we may employ up to 14 stands on a machine which heretofore could accommodate only six pairs of tools.

A further feature, of great importance, is the universal transverse mechanism by which all of the tool stands are simultaneously shifted transversely of the bed upon reversal of the direction of movement of wire. This affords a specialized unitary means for serving one of the purposes heretofore served by the usual individual adjusting screws that are individually operated for independent lateral adjustment of each pair of tools, while in no way interfering with the use of these screws for their other purpose which is slight lateral adjustment of individual knives to shift the cutting edge whenever a working portion gets too dull. The latter purpose is served in our present construction by having each tool stand provided with a rearwardly extending stud 35, from which depends a tail-like extension 36 provided at its lower end with a threaded aperture 37 receiving the threaded rear extremity of a feed screw 39 rotatable and axially shiftable in aligned bearings in the beams 11. Crank handles 40 secured on the square forward ends 41 of the screws 39 afford means for 115 120 125 130

finely adjusting the tools due to the engagement of the feeding threads 38 with the tail pieces 36. These individual adjustments effected by means of the handles 40 permit optional transverse shifting of any stand at any time in order to bring a new portion of the cutting edge of a tool into engagement with the work. Such fine adjustment is superposed on the main simultaneous, stand-shifting adjustment used at each reversal of the wire.

A number of rods 45 have their rear ends loosely secured in openings 46 in the rear beam 11 by pairs of clamping nuts 47. The forward end 48 of each rod 45 is downwardly offset as at 49 and passes under the front beam 11. The loose connection of the rods 45 with the rear beam and the inherent resiliency of the rods permits them to have a slight vertical movement for a purpose which will appear more fully hereafter. Each rod mounts at its projecting end 48 a sectional bearing including a pair of vertically disposed blocks 51 secured on the threaded end of the rod by a nut 52. Blocks 51 cooperate to provide a bearing 53 for a rotatable eccentric 54. A shaft 55 extending longitudinally of the machine has eccentric bearings in the eccentrics 54. Shaft 55 is also accommodated in the transverse bores 56 of blocks 57 depending from the forward ends of the screws 39, blocks 57 being held against longitudinal movement of the screws by collars 58. One or more of the eccentrics 54 is preferably provided with a socket 59 therein, into which a lever (not shown) is adapted to be inserted for the purpose of partially rotating the eccentric. Rotatory movement of the eccentrics 54 will tend to swing the shaft 55 upwardly and rearwardly. Due, however, to the engagement of this shaft with the blocks 57 and the unbending nature of the screws 39 upon which the blocks 57 are fixed, the eccentrics and their bearing blocks will be forced downwardly springing the rods 45. As the shaft 55 passes the dead center position, rods 49 will again spring upwardly assisting in the latter portion of the shaft's movement. Rotation of the eccentrics to shift the shaft from the full line position to the dotted line position of Fig. 2 obviously projects all of the screws 39 rearwardly and consequently shifts all of the tool stands to bring tool sets 27 into engagement over the work on the bed, without interfering with or changing the relative positions of the tool holders with respect to each other. The construction which necessitates forcing the shaft 55 over the dead center against the elastic resistance of the bendable spring rods 45 affords a positive lock to retain the tool stands in either extreme position and eliminates the possibility of any accidental shifting during operation.

The cutter blades may be of an entirely conventional character, consisting of plate-like members having bevelled end faces 27^b cooperating with longitudinally grooved under faces 27^c to provide a series of minute V shaped cutting teeth at the cutting edge 27^d of the tool. These teeth are so fine, usually not more than 5/1000 of an inch that they would be hardly visible to the eye even if the machine were illustrated on a full size 75 scale. Each tool cuts a considerable number of grooves in the wire passing under it and produces a tough steel fibre 60 of minute triangular cross-section.

A feature of the invention is the provision of non-positive means in the nature of air blast nozzles 61 for floating the fibres off the bed and into a hood 62 at the rear of the machine which guides them downwardly into the floor or into a suitable receptacle (not shown). The blast nozzles are located a suitable distance from the wire, midway between adjacent tool stands and are flattened and flared at a proper angle to cool the cutting edges and to take care of fibres or steel wool cut thereby at both ends of the bed block, one lateral edge of the blast floating the fibre cut by tool 27^a when the machine is running in one direction and the other lateral edge of the blast floating wool 90 cut by the tool 27 when the wire is passing in the other direction, while the intermediate portion cools and cleans the wire. Nozzles 61 are fed through vertical feed pipes 65 communicating at their lower end with a horizontal supply pipe 66 extending throughout the length of the machine and receiving air from any appropriate source of supply through a vertical pipe 67 equipped with a valve 68 for controlling the foul of the 100 blast.

Floating fibres to the rear of the machine not only prevents fouling of the cutting tools, but preserves the fibres in a loose, fluffy condition which is highly desirable for packaging purposes. Guard covers 69, 70 may be employed over the stud 35 and the screw feed mechanism for the tool stands to prevent them from becoming fouled by the floating fibres.

In operation a skilled attendant will insert a lever in the socket 59 after each reversal of the wire to simultaneously shift all of the tool stands and bring a reversely facing set of cutting tools over the wire. Since the wire becomes thinned by repeated grooving operations, each shifting of the stands will be followed by rapid and slight adjustment of the tool carrying blocks to lower the cutting tools into engagement with the wire, this adjustment being effected by rotating the heads of the screws 31. The superposition of the adjustment at 37, 38 upon the main tool stand shifting mechanism permits individual tool stands to be 120 125 130

transversely shifted at any time in order to bring new teeth of each cutting edge into engagement with the wire so that the entire cutting edges may be worn down before re-
5 sharpening of the tools becomes necessary.

We thus greatly reduce the time and work required for making adjustments of the knives and further save time, increase the output of a single machine and decrease cost 10 of operation by using a single non-adjustable air blast that relieves the operator of most of the work of caring for the material.

We claim:

1. In a machine of the class described, a 15 bed, reels at opposite ends of the bed adapted to serve alternately as supply and traction reels for dragging a strip of metallic stock alternately in opposite directions across the bed, a plurality of cutter stands 20 having movement transversely of the bed, sets of oppositely facing grooving cutters in the stands and unitary means for shifting all the stands to bring the proper set of cutters into coaction with the work when the 25 direction of movement of the stock is reversed.

2. In a machine of the class described, the combination with a bed and means for pulling a wire alternately in opposite directions 30 over the bed of sets of oppositely facing grooving cutters and means for simultaneously shifting said sets transversely of the bed to bring the proper set of cutters into operation when direction of movement of the stock is reversed.

3. In a machine of the class described, the combination with a bed and means for pulling a wire alternately in opposite directions over the bed of sets of oppositely facing 40 grooving cutters, means for simultaneously shifting said sets transversely of the bed to bring the proper set of cutters into operation when direction of movement of wire is reversed, and means for independently adjusting the depth of cut of each grooving cutter.

4. In a machine of the class described, the combination with a bed and means for pulling a wire alternately in opposite directions over the bed of sets of oppositely facing 50 grooving cutters, means for simultaneously shifting said sets transversely of the bed to bring the proper set of cutters into operation when direction of movement of wire is reversed, and means for independently transversely adjusting each of said cutters to present a new portion of its cutting edge to the material on the bed.

5. In a machine of the class described, a supporting bed, means for moving metal 60 stock alternately in opposite directions over the bed, cutter stands movable transversely above the bed, two sets of cutter holders and grooving cutters, one holder of each set being slidably mounted in each stand for right line adjustment to and from the bed, in com-

bination with means for simultaneously shifting all of the stands to bring the proper set of cutters into position when the direction of movement of the stock is reversed.

6. In a machine of the class described, a 70 supporting bed, means for moving metal stock alternately in opposite direction over the bed, cutter stands movable transversely above the bed, two sets of cutter holders and grooving cutters, one holder of each set being slidably mounted in each stand for right line adjustment to and from the bed, in combination with means for simultaneously shifting all of the stands to bring the proper set of cutters into position when the direction of movement of the stock is reversed, and means for transversely shifting a single stand independently of the common shifting means to present a new portion 75 of the cutting edge of the cutter to the stock.

7. In a machine of the class described, a supporting bed, means for moving metal stock alternately in opposite directions over the bed, cutter stands movable transversely above the bed, two sets of cutter holders and grooving cutters, one holder of each set being slidably mounted in each stand for right line adjustment to and from the bed, in combination with means for simultaneously shifting all of the stands to bring the proper set of cutters into position when the direction of movement of the stock is reversed, and feed screws for independently adjusting each cutter holder in its stand 80 to regulate its depth of grooving.

8. In a machine of the class described, a bed, means for drawing wire stock alternately in opposite directions over the bed, a plurality of cutter stands shiftable transversely of the bed, sets of oppositely facing grooving cutters in the stands and means for vertically adjusting the cutters without changing their cutting angle relative to the stock on the bed.

9. In a machine of the class described, a bed, reels at opposite ends of the bed adapted to act alternately as supply and traction reels for dragging a length of metallic stock alternately in opposite directions across the bed, and a plurality of cutter stands having movement transversely of the bed, blocks vertically adjustable in the cutter stands and sets of oppositely facing grooving cutters, one in each block.

10. In a machine of the class described, a bed, reels at opposite ends of the bed adapted to act alternately as supply and traction reels for dragging a length of metallic stock alternately in opposite directions across the bed, and a plurality of cutter stands having movement transversely of the bed, blocks vertically adjustable in the cutter stands and sets of oppositely facing grooving cutters, one in each block, and feed screws for rais- 115 120 125 130

ing and lowering the blocks without varying the cutting angle of the cutters relative to the work.

11. In a machine of the class described, a bed, means for drawing wire stock alternately in opposite directions over the bed, a plurality of cutter stands shiftable transversely over the bed, sets of oppositely facing grooving cutters in the stands, means for shifting the stands to alternately present the respective sets of cutters in position to operate on the stock, air blast nozzles arranged approximately midway between adjacent stands delivering a fan shaped blast sufficiently wide to float off the bed, fibres cut by adjacent oppositely facing cutters of the respective sets.

12. In a machine of the class described, a bed including a series of spaced adjustable bed blocks having aligned wire guiding and supporting grooves, means for drawing wire stock alternately in opposite directions along said grooves, a plurality of cutter stands shiftable transversely of the bed, sets of oppositely facing grooving cutters in the stands, means for shifting the stands to alternately present the respective sets of cutters in position to operate on the stock, oppositely facing cutters of adjacent stands being adapted to work alternately on opposite ends of a single bed block, and means for delivering an air blast impinging laterally upon each block.

13. In a machine of the class described, a bed including a series of spaced adjustable bed blocks having aligned wire guiding and supporting grooves, means for drawing wire stock alternately in opposite directions along said grooves, a plurality of cutter stands shiftable transversely of the bed, sets of oppositely facing grooving cutters in the stands, means for shifting the stands to alternately present the respective sets of cutters in position to operate on the stock, oppositely facing cutters of adjacent stands being adapted to work alternately on opposite ends of a single bed block, and means for floating fibres off the bed, including a single nozzle arranged adjacent each bed block to deliver transversely a fan-shaped blast of sufficient width to float the fibres cut at each end of the bed block.

14. In a machine of the class described, a bed, means for dragging metallic stock in opposite directions over the bed, cutter stands mounted for movement transversely of the bed, sets of oppositely facing vertically adjustable grooving cutters in the stands, means for shifting the stands to alternately present the respective sets of cutters in position to operate on the stock, and air blast nozzles for floating fibres cut from the stock off the bed of the machine.

15. In a machine of the class described, a bed, means for dragging metallic stock in

opposite directions over the bed, cutter stands mounted for movement transversely of the bed, sets of oppositely facing vertically adjustable grooving cutters in the stands, means for shifting the stands to alternately present the respective sets of cutters in position to operate on the stock, and air blast nozzles for floating fibres cut from the stock off the bed of the machine; a hood at the back of the machine into which the fibres are blown.

16. In a machine of the class described, a bed, means for dragging metallic stock in opposite directions over the bed, cutter stands mounted for movement transversely of the bed, sets of oppositely facing vertically adjustable grooving cutters in the stands, means for shifting the stands to alternately present the respective sets of cutters in position to operate on the stock, air blast nozzles for floating fibres cut from the stock off the bed of the machine, and means for preventing the fibres carried off by the air blast from fouling the carriage shifting mechanism.

17. In a machine of the class described, a bed, means for dragging metallic stock in opposite directions over the bed, cutter stands mounted for movement transversely of the bed, sets of oppositely facing vertically adjustable grooving cutters in the stands, means for shifting the stands to alternately present the respective sets of cutters in position to operate on the stock, air blast nozzles for floating fibres cut from the stock off the bed of the machine, and a guard device around the carriage shifting mechanism to prevent clogging thereof by fibres floated off the bed.

18. In a metal wool machine, means for feeding wire alternately in opposite directions, a cutter stand, a pair of oppositely facing grooving cutters projecting on opposite sides of the stand at fixed angles to the wire, a means for bodily rectilinear adjustment of each cutter toward or away from the wire and means for shifting the stand to bring either set of cutters into operative position.

19. In a metal wool machine of the class described, the combination including a bed over which wire is adapted to be drawn, a plurality of shiftable cutter holders on the bed and oppositely facing cutting tools in said holders, alternately operable as the direction of movement of the wire stock is reversed, means for simultaneously shifting all of the cutting tools, including extensions for the stands, endwise movable rods connected to the extensions, and rotatable eccentric means for simultaneously shifting all of the rods.

20. In a metal wool machine of the class described, the combination including a bed over which wire is adapted to be drawn, a

- plurality of shiftable cutter holders on the bed and oppositely facing cutting tools in said holders, operable as the direction of movement of the wire stock is reversed, means for simultaneously shifting all of the cutting tools including extensions for the stands, endwise movable rods connected to the extensions and rotatable eccentric means for simultaneously shifting all of the rods; each of said rods having threaded engagement with its tool carriage extension whereby to permit fine transverse independent adjustment of each carriage by rotating their respective rods.
21. In a metal wool machine of the class described, the combination including a bed over which wire is adapted to be drawn, a plurality of shiftable cutter holders on the bed and oppositely facing cutting tools in said holders, alternately operable as the direction of movement of the wire stock is reversed, means for simultaneously shifting all of the cutting tools including extensions for the stands, endwise movable rods connected to the extensions, and rotatable eccentric means for simultaneously shifting all of the rods; and means for individually shifting any of said carriages for adjustment purposes independently of the action of said rotatable eccentric means.
22. In a metal wool machine of the class described, the combination including a bed over which wire is adapted to be drawn, a plurality of shiftable cutter holders on the bed and oppositely facing cutting tools in said holders, alternately operable as the direction of movement of the wire stock is reversed, means for simultaneously shifting all of the cutting tools including extensions for the stands, endwise movable rods connected to the extensions, and rotatable eccentric means for simultaneously shifting
- all of the rods; and means for independently vertically adjusting all of the cutting tools to regulate their depth of cutting. 45
23. In a steel wool machine of the class described, a bed, means for drawing a length of wire alternately in opposite directions over the bed, cutter stands on the bed, oppositely facing grooving cutters mounted 50 for vertical adjustment in the stands, shifting mechanism for simultaneously transversely shifting all of the stands, said mechanism including automatic locking means for retaining the stands in either extreme 55 position.
24. In a steel wool machine of the class described, a bed, means for drawing a length of wire alternately in opposite directions over the bed, cutter stands on the bed, oppositely facing grooving cutters mounted 60 for vertical adjustment in the stands, shifting mechanism for simultaneously transversely shifting all of the stands, said mechanism including automatic locking means 65 for retaining the stands in either extreme position, said locking means including an eccentrically movable shift bar and spring means opposing the shifting of the bar from one extreme position to the other. 70
